CLAIM

The ornamental design for a display screen or portion thereof with graphical user interface, as shown and described.

DESCRIPTION

FIG. 1 is a front view of a first image in a sequence of display screen or portion thereof with graphical user interface; and,

FIG. 2 is a front view of a second image in the sequence of the display screen or portion thereof with graphical user interface.

The features shown in evenly broken lines represent portions of the graphical user interface that form no part of the claimed design. The dot-dash broken lines illustrate boundaries of the display screen or portion thereof.

1 Claim, 2 Drawing Sheets

Auto Trueplay

Your <product name>'s microphone is used for more than voice control. Auto Trueplay uses it to tune for your surroundings.

<Product name> starts retuning when you pick it up, and continues to adapt to your environment as long as the microphone is on.
